UNITED STATES PATENT OFFICE.

RINALDO ALDEN, OF CHICAGO, ILLINOIS.

ORGAN-STOP KNOB.

SPECIFICATION forming part of Letters Patent No. 372,649, dated November 8, 1887.

Application filed February 24, 1887. Serial No. 229,462. (No model.)

To all whom it may concern:

Be it known that I, RINALDO ALDEN, residing at Chicago, in the county of Cook and State of Illinois, and a citizen of the United States, have invented a new and useful Improvement in Organ-Stop Knobs, of which the following is a full description.

The object of my invention is to produce an organ-stop knob which shall be cheap, durable, and sightly, and free from liability of splitting while in use. I attain this object by the mechanism illustrated in the accompanying drawings, in which—

Figure 1 shows a top view of my improved knob; Fig. 2, a side view of the same; Fig. 3, a section through the line $x\ x$; and Fig. 4 is a vertical central section of the metal ring.

Referring to the drawings, in which similar letters refer to like parts, D is the knob, provided with the sunken top and sloping sides, as shown in Fig. 3. A is a metal ring provided with the flange e. The ring A fits over the knob D and holds the name plate B in position.

My improved knob is constructed as follows, *viz.:*

The name plate B, of diameter a little greater than that of the top face of the knob, is placed in position so that its outside edge 30 rests against the sloping sides of the top of the knob, its under surface being a little distance above the top face of the knob. The ring A is then placed over the knob so that the flange e rests upon the upper outside edge of the plate

35 B. The lower edge, a, of the ring is then spun down, around, and into the yielding material of the knob, as shown in Fig. 2, while, by

reason of the curved shape of the outside of the knob, the plate B is firmly compressed into the sloping sides of the top of the knob 40 until it rests on the top face thereof, by reason of the contact of the flange e with the plate B. The outside of the ring A is then deeply milled or tooled, so that the inside surface of the ring is roughened and depressed into the body of 45 the knob, to prevent the ring from turning around the knob, and thereby displacing the name-plate, so that the name of the stop could not be easily read.

The edge a of the ring, being sunk into the 50 material of the knob until its outside surface is flush with the surface of the knob, forms a smooth face, free from all liability of cutting or injuring the fingers when the knob is in use. The ring A also serves, when seated in position, as above described, as a binder to prevent the knob from checking or splitting while 55 in use.

I am aware that knobs have heretofore been made by compressing a ring around the top 60 and sides thereof to hold a plate in position; hence I do not claim that feature, broadly.

What I do claim, and desire to secure by Letters Patent, is—

In an organ-stop knob, the combination of 65 the knob D, provided with a sloping interior top, the plate B, the ring A, provided with the flange e, and milling b, substantially as described, and for the purposes set forth.

RINALDO ALDEN.
